UNITED STATES PATENT OFFICE.

HERMAN C. PRIEBE, OF BLUE ISLAND, ILLINOIS.

DRAFT-GEAR.

1,248,399.

Specification of Letters Patent. Patented Nov. 27, 1917.

Application filed December 6, 1915. Serial No. 65,212

To all whom it may concern:

Be it known that I, HERMAN C. PRIEBE, citizen of the United States, residing at Blue Island, in the county of Cook and State of Illinois, have invented a certain new and useful Improvement in Draft-Gears, of which the following is a full, clear, concise, and exact description, reference being had to the accompanying drawings, forming a part of this specification.

My invention relates to draft gears and has a number of objects and advantages in view.

The invention has for one of its objects the provision of a coupler butt attachable to the inner end of the shank of a standard coupler. The inner end face of the shank of a standard coupler is provided with a hole communicating with the hollow interior of the coupler shank and into this hole I fit the shank of a horizontally slotted coupler butt. Thus the shank of a standard coupler may be provided with a slot formation added for the purpose of adapting it for engagement with the front or outer follower from which the coupler shank may be pulled but against which follower the coupler shank may be pushed and in the slot of which coupler butt the front follower is movable in rounding curves and for other purposes. The invention has for another of its objects the formation of a coupler butt that is in flexible connection with the coupler shank that carries it which desirably also has relatively movable and sliding connection with the outer follower, this construction enabling the coupler shank to occupy varying positions with respect to its butt and also with respect to the outer follower engaged by its butt.

The invention also has for its object the provision of a preferably similar member constituting a preferably flexible part of a stop at the inner end of the yoke and serving to engage the yoke in such a manner that the inner end of the yoke may have varying positions with respect to its inner abutment. This construction at the inner end of the yoke also enables me to hold the inner end of the yoke in its proper plane against the action of motion resisting mechanism that may be correlated with the coupler yoke.

The invention also has for its object the provision of a coupler yoke whose sides are preferably disposed in substantially parallel vertical planes instead of substantially hori-

zontal planes, by means of mechanism which does not entail the employment of an inner key and the slotting of the center sills to accommodate such key.

I will explain my invention more fully by reference to the accompanying drawings showing the preferred embodiment thereof and in which Figure 1 is a plan view, partially in section, Fig. 2 is a view in elevation, partially in section, on line 2-2 of Fig. 1; Fig. 3 is a sectional view on line 3-3 of Fig. 1; Fig. 4 is a perspective view of a yoke entering into the construction; Fig. 5 is a view showing the construction of the center brace that is fastened to the center sills and which bears upon the bolster; and Fig. 6 is a perspective view of a fitting that is employed at the front and rear of the gear.

Like parts are indicated by similar characters of reference throughout the different figures.

The coupler 1 includes a shank 2, which is connected with a yoke structure in a manner later to be set forth, the sides of the yoke structure shown being in the form of straps 3 through which openings 4 and 5 are provided for the reception of keys 6 and 7, the former of which constitutes a form of follower, the openings permitting the keys to move inwardly with respect to the yoke when the coupler is subject to a sufficient pushing strain. The keys also project through openings 8 and 9 in the cheek plates 10 and 11 which are secured to the center sills 12 and 13, the openings 9 registering with the openings 5 and corresponding openings in the center sills when the gear is not under stress, the openings 8 similarly registering with the openings 4 and similar openings in the center sills.

Cotter pins 14 may be employed to prevent the withdrawal of the keys from the slots in the center sills that receive them. The rounded opposed transverse edges of the follower 6 and yoke end 3¹ are received within semicylindrical pockets 15, 16 that are formed in the stems of rockers 17 and 18, there being outwardly diverging arms 19, 20, 21 and 22 between which the elements 6 and 3¹ are disposed as illustrated. The rockers have direct engagement with each other and the opposed faces thereof are curved or cam shaped so that each rocker will co-act with the other and serve as a resistance therefor to force the rockers to swing, in a vertical plane upon coupler

movement. The motion resisting mechanism shown includes a spring structure 24 resting upon a seat 25, the spring mechanism being illustrated as occupying a place between the center sills. The spring mechanism includes a rigid abutment plate 26 near the tops of the center sills and against which abutment plate the springs operate to press the spring seat 25 upon the rockers. Each 10 rocker has a nose 27 that is curved upon its top to have rolling engagement with the bottom face of the spring seat and is curved on its bottom to have rocking engagement with the rocker that it engages. When the 15 gear is not under stress the nose upon each rocker serves to hold the other rocker in its lowermost position, the noses coöperating to relieve the abutting faces of the rockers as far as possible of pressure due to spring 20 action.

The coupler butt 1¹ has an outsetting cylindrical stem 28 which is co-axial with the coupler shank and passes through a hole in said shank, this hole being preferably of 25 larger diameter than the stem so that the coupler butt may universally swing with respect to the stem to maintain its full engagement with the follower 6 during the various swinging movements of the coupler 30 shank, the coupler butt being thus flexibly connected with the inner end of the coupler shank. The transverse slot 1² in the coupler butt permits the coupler butt to shift along the follower 6 while maintaining full engagement therewith and also permits the coupler shank to move outwardly when the outer follower 6 is held against its forward stops.

A similarly constructed and flexibly connected but symmetrically arranged fitting 29 receives in its slot the inner end 3¹ of the yoke 3, the yoke thus having sliding connection with the butt 29. The inner end 3¹ constitutes a member connecting the inner 45 ends of the sides of the yoke. A stem 30 projects inwardly (that is toward the center of the car) from the butt 29 and is loosely received within the recess 31 in the center brace 32 that bears upon the body bolster 50 center plate 33. The center brace receives the bolster pin 34, the position of the center brace illustrated being somewhat unusual as the drawings are taken from a special construction, it being understood, however, 55 that the invention is not to be limited to this special construction. The stem receiving opening 31 is formed within an abutment 35, this abutment 35 engaging the butt 29 and upon which abutment the butt 29 may oscillate and slide, and in the event of wear liners may be employed or other adjusting means may be used to effect compensation for such wear. The center brace is also desirably provided with oblong recesses 36 in 60 which portions of the inner end of the cou-

pler yoke may be received. In the embodiment of the invention illustrated the coupler yoke is provided with lugs 37 that are received within the transverse recesses or slots 36, said lugs and recesses coöperating to maintain the inner part of the coupler yoke in a substantially horizontal plane whereby the proper position of the inner part of the coupler yoke is not disturbed by the rockers 17 and 18 and the spring mechanism 24 but is substantially maintained in the line of draft. Thus the center brace 32 acts as a stop to confine the coupler yoke to its proper plane. The end walls of the recesses 36 also act as stops to limit the inward movement of the coupler yoke, thereby coöperating with the abutment 35. By the construction now being described the use of keys at the inner end of the coupler yokes is avoided and the slotting of the center sills and side 85 members of coupler yokes at the inner ends of the coupler yokes is likewise dispensed with since the center brace and the construction of the coupler yokes illustrated afford the desired limit to the inward movement of the coupler yokes while permitting the coupler yokes to have forward or outward movement when the couplers are subject to sufficient pull. While I have employed a center brace 32 that serves to receive the bolster pin I do not wish to be limited to a center brace that performs this added function nor to any peculiar construction or other draft lug construction that performs the functions herein set forth. 90

The rockers 17 and 18 are disposed between the sides of the yoke that serve to maintain the rockers from displacement laterally of the gear when the rockers are not rocked upwardly. When the rockers are 100 rocked upwardly, the upper parts thereof project above the coupler yoke and in order further to insure against lateral separation of the rockers when they are upwardly rocked I provide downsetting fingers 38 upon the spring seat 25, each finger being individual to a rocker and freely projecting into a recess in the upper portion of each associate rocker there to guard against lateral movement. 110

Certain structural characteristics herein shown are claimed in my co-pending applications, Serial No. 28,660, filed May 17, 1915, Serial No. 28,661, filed May 17, 1915, and Serial No. 59,333, filed November 3, 1915. 115

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:— 120

1. A draft gear including a coupler, an 125

outer follower; and a coupler butt flexibly connected with the inner end of the coupler shank and having a transverse slot receiving said follower.

5. A draft gear including a coupler having a shank; an outer follower; a coupler butt having a stem received in the inner end of the coupler shank, this coupler butt having a transverse slot in which the outer follower may operate.

10. A draft gear including a coupler; a coupler yoke, said coupler yoke having a member connecting the inner ends of the sides of the coupler yoke; center sills between which the aforesaid gear parts are located; an abutment structure within the space between the center sills, this abutment structure having an element which is slotted and in the slotted portion of which the afore-

15. said inner end of the sides of the coupler yoke operates; and a butt loosely received by said abutment structure and having a slot formed therein receiving the connecting member.

20. A draft gear including a coupler; a coupler yoke, said coupler yoke having an inner end joining the sides of the coupler yoke; an inner abutment; and a flexibly mounted butt supported by the abutment having a slot formed therein receiving the inner end of the yoke.

25. In witness whereof, I hereunto subscribe my name this third day of December, A. D. 1915.

HERMAN C. PRIEBE.
